UNITED STATES PATENT OFFICE.

LEWIS Y. MYERS AND WILLIAM M. MOUNTAIN, OF CANTON, OHIO, ASSIGNEES OF ONE-THIRD OF THEIR RIGHT TO ALEXANDER HURFORD, OF SAME PLACE.

HORSE HAY-FORK.

SPECIFICATION forming part of Letters Patent No. 227,041, dated April 27, 1880.

Application filed May 6, 1879.

To all whom it may concern:

Be it known that we, LEWIS Y. MYERS and WILLIAM M. MOUNTAIN, of Canton, in the county of Stark and State of Ohio, have 5 invented certain new and useful Improvements in Hay-Forks; and we do hereby declare that the following is a full, clear, and exact description of the invention, which will enable others skilled in the art to which it appertains to 10 make and use the same, reference being had to the accompanying drawings, which form a part of this specification.

Figure 1 is a plan view of the fork open. Fig. 2 is a plan view of the fork closed; and 15 Fig. 3 is a vertical cross-section.

Corresponding parts in the several figures are denoted by like letters of reference.

This invention relates to hay-forks; and it 20 consists in certain improvements in the construction of the same, which will be herein-after fully described, and particularly pointed out in the claim.

In the drawings, A represents a sharp-pointed rod or spear, to the head of which is 25 secured a block, B, having the pulley C, by means of which the device is adapted to be hoisted in the usual manner.

D is a cap or box sliding upon the rod A and provided with side flanges, E E, to which 30 the hooks F F are hinged or pivoted. The front side of the box D is provided with a suitably-constructed latch or catch, G, engaging a notch, H, in the upper end of rod A, and operated by a cord or rope, I.

The lower end of rod A is provided with a 35 notch, R, engaging a spring-catch, Q, in the rear side of box D, by which the box is prevented from sliding off the rod.

J J are ropes or cords connecting the hooks 40 F F with the block B, which is provided with perforated flanges K K, for the attachment of said cords.

To operate our improved hay-fork, which is 45 supposed to be suspended by pulley C from suitable tackle, the rope I is first pulled so as to disengage catch G from notch H. By continuing the pull the box D is slid down to the end of rod A, the latch above mentioned

preventing it from coming off. The fork is now lowered until the point of the spear enters the hay. The pressure of the hay will then gradually slide the box D up toward the head of the spear, thus closing the hooks together and causing them to grasp a load of hay. When the box D reaches the head the 55 catch G engages the notch H, thus locking the fork and enabling it to be elevated with the load.

We are aware of the patent to Raber, No. 94,644, September 7, 1869, and we claim nothing therein shown.

It will be observed that in our invention the end of the latch or lever G to which the trip-rope is attached is below the fulcrum, thereby causing the said latch to be disengaged by a downward pull upon the trip-rope, which, when continued, draws the sliding head D down, thus spreading the forks and dropping the load. This is an important advantage, because if the load should be 70 small or the hay damp considerable difficulty is experienced in dropping the load, unless some power can be brought to bear direct upon the sliding head.

Again, by constructing the head D with the 75 spring-catch Q the said head, while prevented from coming off the spear by accident, may be easily removed at any time for repairs, &c., by simply fitting a wedge in the recess R, when the head will readily slide off.

Having thus described our invention, we 80 claim and desire to secure by Letters Patent of the United States—

In a horse hay-fork, the combination of the spear A, having notch R, and the sliding head 85 D, having spring-catch Q, adapted to engage said notch R to prevent head D from sliding off spear A, as set forth.

In testimony that we claim the foregoing as our own we have hereto affixed our signatures in presence of two witnesses.

LEWIS Y. MYERS.

WILLIAM M. MOUNTAIN.
